UNITED STATES PATENT OFFICE.

JOHN LJUNG, OF ALEXANDRIA, MINNESOTA.

SAW-VISE.

No. 918,338.

Specification of Letters Patent.

Patented April 13, 1909.

Application filed April 21, 1908. Serial No. 428,429.

To all whom it may concern:

Be it known that I, JOHN LJUNG, a citizen of the United States, residing at Alexandria, in the county of Douglas and State of Minnesota, have invented a new and useful Saw-Vise, of which the following is a specification.

The invention relates to improvements in saw vises.

The object of the present invention is to improve the construction of saw vises, and to provide a simple, inexpensive and efficient one of great strength and durability, adapted to clamp uniformly throughout its length either narrow or wide bladed saws without permitting one end of a saw blade to vibrate loosely within it when the teeth of the saw are being filed.

Another object of the invention is to provide a saw vise having a pivotally mounted saw clamp, adapted to be arranged at different angles or inclinations and secured in its adjustment by the means for attaching it to a bench or other support.

With these and other objects in view, the invention consists in the construction and novel combination of parts hereinafter fully described, illustrated in the accompanying drawings, and pointed out in the claims here-to appended; it being understood that various changes in the form, proportion, size and minor details of construction, within the scope of the claims, may be resorted to without departing from the spirit or sacrificing any of the advantages of the invention.

In the drawings:—Figure 1 is a perspective view of a saw vise, constructed in accordance with this invention. Fig. 2 is a side elevation, showing the opposite side of the saw vise. Fig. 3 is a side elevation of the saw vise, illustrating the manner of clamping a wide bladed saw. Fig. 4 is a vertical sectional view on the line 4—4 of Fig. 3. Fig. 5 is a horizontal sectional view on the line 5—5 of Fig. 3. Fig. 6 is a detail perspective view of the angle locking lever.

Like numerals of reference designate corresponding parts in all the figures of the drawings.

The saw vise includes a saw clamp provided with a horizontal pivot 1, adapted to permit the saw clamp to be arranged at different angles and inclinations, and supported by a bench clamp, composed of an upper straight horizontal member 2 and a substantially L-shaped member 3, consisting of a

vertical arm or portion and a horizontal arm or portion. The upper horizontal member is provided at one end with a jaw 4 for engaging the upper face of a bench 5, or other suitable support, and the other end of the member 2 is provided with a slot or bifurcation 6, which receives the upper end of the vertical portion of the L-shaped member. The upper end of the vertical portion of the L-shaped member 3 and the bifurcated end of the horizontal member 2 are provided with registering openings for the reception of the pivot 1. The lower horizontal arm of the L-shaped member is provided with a threaded opening 7 for the reception of a clamp or thumb screw 8, pivotally connected at its upper end to a horizontal jaw 9 for engaging the lower face of the bench 5. The lower end of the screw 8 is provided with a suitable head for enabling it to be readily grasped and operated. The L-shaped member is provided at the upper end or portion of its vertical arm with opposite shoulders 10, and the sides of the bifurcation 6 have straight edges 11, which engage the shoulders 10, whereby when pressure is applied by the screw 8, pressure will be transmitted to the pivot 1, which will be frictionally clamped by the members 2 and 3 of the bench clamp with sufficient force to hold the saw clamp in its adjustment.

The saw clamp is provided with a substantially U-shaped body 12, having one of its arms extended above the other and carrying a relatively fixed jaw 13, formed integral with the U-shaped body of the clamp. The jaw 13 is V-shaped in cross section and cooperates with a corresponding V-shaped jaw 14, arranged in substantial parallelism with the jaw 13 and adapted to fit within the same, as clearly shown in Figs. 1 and 2 of the drawings to clamp a narrow saw blade. When it is desired to clamp a key hole saw, or similar narrow bladed saw, the jaws are arranged with their outer coöperating portions in vertical planes. The U-shaped body portion is arranged at an inclination, when the outer engaging portions of the jaws 13 and 14 are vertical. When it is desired to clamp a wide bladed saw, such as an ordinary carpenter's saw, the body portion of the saw clamp is arranged in a vertical position and the jaws are moved beyond an interfitting position to provide a clear space between them, as shown in Fig. 3 of the

drawings. This brings the wings or sides of the V-shaped jaws in an inclined position, the relatively fixed jaw presenting two engaging edges to the saw blade, and the movable jaw presenting a single engaging edge located at an intermediate point between the upper and lower engaging edges of the fixed jaw. When the saw clamp is arranged in this position, it is adapted to 10 accommodate a wide blade, which may extend into the space between the sides of the U-shaped body 12.

The movable or adjustable jaw 14 is formed integral with a central shank 15, pivoted at an 15 intermediate point to the upper end of the short side of the U-shaped body by a bolt 16, or other suitable fastening device and forming a lever. The lever formed by the shank has a short upper arm and a long lower or 20 depending arm, which is adapted to be engaged by an angle locking lever 17. The angle locking lever 17, which consists of a short arm 18, arranged at an angle to the long arm, is fulcrumed at its angle on the body 25 12 at the bottom thereof by means of a bolt 19, or other suitable pivot. The body is provided at its lower portion with a boss 20, which spaces the angle locking lever from the body to provide a space for the shank or 30 lever of the adjustable jaw. The lower or depending arm of the shank or lever 15 is provided at its lower portion with a notch 21, located at the inner edge of the shank and adapted to be engaged by studs 22 and 35 23. The stud 23 projects from the inner face of the long arm of the angle locking lever, and is adapted to engage the said notch 21 when the jaws 13 and 14 engage a saw having a wide blade. The other stud 22, which is 40 located a greater distance from the pivot 19 than the stud 23, projects from the inner face of the short arm 18 of the locking lever and engages the recess or notch 21, when the jaws 13 and 14 are arranged for clamping 45 a narrow saw blade. The lower arm of the shank or lever 15 is also provided with a stop 24, consisting of a stud and arranged to be engaged by the locking lever to limit the upward swing of the long arm of the 50 same.

The jaws, whether engaging a wide saw blade or a narrow saw blade, fit against the same and uniformly clamp the saw blades throughout their entire length so that one 55 end or portion of the saw blade will not be left free and permitted to vibrate when the saw teeth are filed. The pivotal movement of the saw clamp enables the angular or V-shaped jaws to be arranged for holding 60 either a wide or narrow blade in a vertical position and by tightening the screw 8, sufficient pressure is produced on the pivot 1 of the saw clamp to hold the latter in its adjustment while the saw teeth are being 65 filed.

Having thus fully described my invention, what I claim as new and desire to secure by Letters Patent, is:—

1. A saw vise including a saw clamp provided with a pivot, and a bench clamp composed of two members connected together by the said pivot and having means for engaging each other, and adjusting means carried by one of the clamp members and co-operating with the other to engage a bench 75 or support and adapted also to produce pressure on the pivot for holding the saw clamp in its pivotal adjustment.

2. A saw vise including a saw clamp having a pivot, and a bench clamp composed of 80 two members connected together by the said pivot and supporting the saw clamp, one of the members being provided with a shoulder arranged to be engaged by the other member, and adjustable means mounted on one 85 of the said members and co-operating with the other to engage a bench and to produce pressure on the pivot.

3. A saw vise including a saw clamp having a pivot, and a bench clamp composed of 90 two members connected together by the said pivot, one of the members being bifurcated to receive the other and the latter member having opposite shoulders for engaging the bifurcated member, and adjusting means 95 mounted on one of the members and co-operating with the other for clamping a bench and to produce pressure on the pivot.

4. A saw vise including a saw clamp provided with corresponding angular jaws arranged to interfit and movable also beyond each other to provide a clear intervening space between them, and means for adjustably mounting the saw clamp to arrange the jaws to present either flat faces or engaging 105 edges to a vertical saw blade.

5. A saw vise including a saw clamp provided with substantially V-shaped jaws composed of angularly related sides or wings and arranged to interfit and movable 110 also beyond each other to provide a clear intervening space between them, and means for adjusting the saw clamp to present flat vertical faces to a narrow vertical saw blade or opposite engaging edges for holding a 115 wide saw blade in a vertical position.

6. A saw vise including a saw clamp composed of an approximately U-shaped body, and co-operating jaws located at opposite sides of the top of the body, said jaws being approximately V-shaped in cross section and having their sides or wings arranged at an angle to the sides of the body.

7. A saw vise including a saw clamp composed of a body having a fixed jaw, a movable jaw provided with a shank pivoted to the body, and a locking lever pivoted to the body and provided with studs located at different distances from the pivot of the locking lever and arranged in different radial di- 125 130

rections to successively engage the shank of the movable jaw to hold the latter in a plurality of adjustments.

8. A saw vise including a saw clamp composed of a body having a fixed jaw, a movable jaw having a shank pivoted to the body, and a locking lever pivoted to the body and having a short arm arranged at an angle to the body portion of the lever, and studs 10 mounted on the short arm and on the body portion of the lever and located at different distances from the pivot of the same and arranged to successively engage the shank of the movable jaw.
- 15 9. A saw vise including a saw clamp composed of a body having a fixed jaw, a movable jaw provided with a shank pivoted to the body and having a notch, an angle locking lever pivoted at its angle to the body and 20 provided with studs mounted on its arms in position to successively engage the notch for locking the movable jaw in a plurality of adjustments, and a stud projecting from the shank of the movable jaw for limiting the 25 swing of the locking lever.

10. A saw vise comprising a saw clamp including two relatively movable jaws and having a pivot, and a bench clamp composed

of two relatively movable members connected together by the said pivot and having adjusting means for causing the said members to engage a bench, one of the said members being also provided with means for preventing the other from moving around the pivot, whereby when pressure is applied by the 35 screw it will be transmitted to the pivot to hold the saw clamp in different positions.

11. A saw vise comprising an adjustable saw clamp having a horizontal pivot, and a bench clamp comprising an upper horizontal 40 member, a substantially L-shaped member connected with the horizontal member by the said pivot, and a clamping screw mounted on the L-shaped member and coöperating with the other member to clamp a bench, 45 said members being provided with coöperating engaging portions and adapted to frictionally engage the pivot for securing the saw clamp in different positions.

In testimony that I claim the foregoing as my own, I have hereto affixed my signature in the presence of two witnesses.

JOHN LJUNG.
